UNITED STATES PATENT OFFICE.

DAVID E. VANVACTOR, OF ARGOS, INDIANA.

MACHINE FOR THREADING BANDS IN STAVES.

No. 927,696.

Specification of Letters Patent.

Patented July 13, 1909.

Application filed July 18, 1908. Serial No. 444,285.

To all whom it may concern:

Be it known that I, DAVID E. VANVACTOR, a citizen of the United States, residing at Argos, in the county of Marshall and State 5 of Indiana, have invented certain new and useful Improvements in Machines for Threading Bands in Staves, of which the following is a description, reference being had to the accompanying drawings, forming 10 a part of this specification, in which corresponding characters of reference in the different figures indicate like parts.

The object of my invention is to provide a machine for threading one or more bands or 15 wires through holes in staves for the formation of posts, columns and other structures, the bands or wires being supplied preferably from a continuous roll or rolls, one of which is provided for each band along the length 20 of the column; the requisite number of staves for a given post being assembled and supported in a suitable form constituting a part of the machine, said form being so constructed as to permit the bands to enter the 25 holes in the first and to protrude from those in the last stave.

Further objects are to provide means for simultaneously feeding any predetermined 30 number of bands requisite for a column of given length, for imparting thereto the proper curve to cause them to follow the holes in the successive staves, in the event that said holes are curved, for severing said bands when threaded, so as to enable the 35 opposite ends to be connected to bind the staves together, and for so pointing or shaping the severed ends as to facilitate the threading,—the severing and shaping of all the bands threaded being also simultaneous. 40 Moreover it is my object to provide means for automatically stopping the machine when the requisite length of wire is fed thereto.

I accomplish said objects by means of the 45 combined elements hereinafter more particularly described and definitely set forth in the claims.

In the drawings, Figure 1, is a transverse vertical sectional view showing a supporting standard and stave-holding form for holding staves in position to be threaded, the staves, as well as the band - feeding mechanism being shown as sectioned in the 50 plane of one of the bands, Fig. 2, is a 55 plan view, partly in section, of a portion of

the machine, showing parts of two of the stave-holding forms, corresponding feed rolls, and the automatic stopping device for arresting the action of the driving mechanism when requisite lengths of bands are fed 60 through the staves, portions of the guiding and cutting mechanism being removed, Fig. 3, is a transverse vertical sectional view taken upon the line 3—, Fig. 2, Fig. 4, is a like sectional view taken upon the line 4—, 65 Fig. 2, Fig. 5, is a section view taken upon the line 5—, Fig. 1, viewed in the direction of the arrow there shown, Fig. 6, indicates a section taken upon the line 6—6, Fig. 5, Fig. 7, is a view of the levers for actuating 70 the band cutting and swaging mechanism, Fig. 8, is a perspective view of one of the cutting and forming dies, Fig. 9, is a central longitudinal sectional view of the stave-holding form, taken upon the line 9—9, 75 Fig. 1, Fig. 10, is an enlarged vertical section corresponding to a portion of the view represented in Fig. 1, showing the wire bending rolls and one of the wire cutting and forming dies, and Fig. 11, is a plan view, 80 partly in section, of a modified construction representing a simple form of driving mechanism, said view being represented as if taken upon line 11—11, Fig. 1.

Referring to the drawings, 1, Figs. 1, 2 85 and 3 represents a horizontal bed-plate consisting of a flat bar extending throughout the length of the machine. Said bed-plate is supported upon suitable standards 1^a, which are rigidly attached to the floor; the 90 number being varied to conform to the length of the machine. Bolted to the upper face of the bed-plate 1 are a series of short standards 1^a, Fig. 1, to the upper end of each of which is bolted a stave-holding form 95 generally designated by 2, Figs. 1, 2, 9 and 10, said form being composed of two parts 3 and 4, the former of which is bolted to said bed-plates as stated, while the latter is hinged thereto as shown at 5, Figs. 1 and 2. 100 A latch 6, mounted upon an eccentric 7, fitted in lugs 8 upon the part 4, is adapted to engage a pin 9, upon lugs 10, formed upon the part 3, which enables the two parts of the form to be locked together for the purpose 105 hereinafter stated. Passing through the series of forms lengthwise of the machine, is a removable rod 11, upon which is mounted a plurality of counterpart forms or cores 12, which correspond in number to, and coin- 110

cide with the forms 2, to the periphery of each of which cores is secured, within a groove, a yielding cushion 13, preferably formed of india rubber or other elastic material, for the purpose hereinafter stated. The inner face of each of the several forms 2 comprising the parts 3 and 4, is, in the preferred construction shown, made to describe a volute, to which the outer face of the core 5 forms a counterpart, the space between being intended for the reception of the staves 14, which are held therein in convolute form. In order to insert the staves, the parts 4 are unlatched and thrown back, the rod 11, with 10 the cores 12 thereon removed, when the staves 14, are laid into the lower half of the form, edge to edge with their backs resting against the inner faces of the parts 3. The rod 11, with the cores, is then placed in position, with the staves thus located, when additional staves necessary to form the intended structure are placed in position with 15 their inner faces against the core.

My improved machine is adapted to operate upon staves previously punched or bored 20 for the reception of bands, the holes therein having been gaged from the back face, as well as from an abutting end. Said staves are, therefore, placed in the machine with 25 the same ends from which they were gaged when punched, abutting against a stop 14^a, Fig. 2, which consists of a vertical plate having horizontal supports 14^b, rigidly attached thereto and provided with slots 14^c, for the 30 reception of bolts 14^d, by means of which it may be adjustably and rigidly attached to the bed-plate. The adjustable feature enables the stop to be so placed as to cause the 35 holes to register with the band feeding guides hereinafter described. When the staves are properly placed in the forms and gaged, the parts 4 of the forms are closed and locked by means of the latches 6. The inner 40 faces of the staves being thereby firmly pressed against the yielding elastic cores, which results in pressing the back faces of 45 the staves against the inner faces of the encircling forms and insuring an accurate registration of the holes in the adjacent staves; it being understood that any variation in 50 the thickness of the staves is provided for by the action of the elastic cores.

In the example illustrated, it will be seen 55 that the staves are accurately supported in convolute form with the meeting edge of the last stave outside of and away from that of the first, so as to permit the ends of the bands to enter the holes in the former, and to protrude from those in the latter.

60 A threading guide, generally designated by 15, Figs. 1, 5 and 10, is formed upon and adjacent to each of the parts 3, said guide having a bore 16 therein, which is tangential to and in registration with the bores in the 65 staves. Bearings blocks 17, Fig. 1, are bolt-

ed to depending extensions upon the parts 3, in which blocks are supported parallel shafts 18 and 19.

The driving shaft 18, which will be hereinafter referred to in describing the automatic stop mechanism, is connected with the driven shaft by means of intermeshing gears 20, 21, by which they may be caused to rotate in unison. A slide block 22, better shown in Fig. 11, adapted to be adjusted by 70 means of a set-screw 23, is arranged to bear against the shaft 19, for purposes of adjustment. Feed rollers 25, 26, Figs. 1, 2 and 5, are mounted upon the shafts 18 and 19, opposite to the several guides 15. Said feed rollers are provided with counterpart peripheral grooves 27, so placed that the space between them will register with the bore 16, in the guide 15. Said grooves are adapted 80 to receive a wire 28, Figs. 1, 5, 6, 9 and 10, and feed it into the guide bore 16, and thence into the bores formed in the staves, as shown in Fig. 1.

By means of the set-screw 23, and block 22, the pressure of the feed-rolls upon the 90 wire may be adjusted as desired, a spring 23^a in conjunction with bar 23^b, being interposed to avoid any possible variation in pressure which might arise from irregularity 95 in the rolls.

It is obvious that, if the wire were left straight, it might fail to follow the curved stave holes and thereby defeat the object intended. It is, therefore, essential in the 100 construction shown, that it should be given such a bend as will cause it to follow the curve of the holes without deflection. This result may be accomplished by the following means: Formed in the upper portion of the guide element are recesses 28^a, 29 and 30, better shown in Fig. 10, which communicate with the bore 16; the recess 30 being upon the opposite side of said bore from the others. Rollers 31, 32 and 33, are mounted upon suitable bearings in said recesses respectively, the roller 33, being upon the opposite side of the bore 16, from the others and having its axis in a plane midway between them. The roller 32, has its bearing in a U-shaped support 34, which, in turn, is connected with 105 an adjusting screw 35, tapped into the fitting or frame portion. By turning said screw, any desired pressure may be made against the wire, thereby imparting thereto 110 the requisite curve.

Having described the parts for holding the staves and for feeding, bending and threading the wire, with the exception of the automatic mechanism, I will now describe the means for cutting the wires and 115 forming the ends. Slidably fitted in a horizontal hole formed in the wire guide behind the bending rolls, and coinciding with the path of the wire, are oppositely disposed cutting dies, generally designated by 36 and 120 130

37, Figs. 1, 5, 6, 8 and 10. The meeting ends of said dies are provided with counterpart cutting edges 38, better shown in Fig. 8, which converge at the center, and are also provided with notched portions 39 between said cutting edges and arranged in the plane of the axis of the wire. Said cutting edges serve, when the cutters are forced together, not only to sever the wire, but to cut notches 5 from opposite sides thereof, so that if the wire were not swaged, each of the severed ends would be wedge-shaped. Simultaneously, however, with the cutting action, the notched dies 39, are forced against the opposite edges of the wedge and serve to swage them so that the tapered portion is made round with a somewhat blunt pin-point. Upon the outer end of each of the parts 36, and 37, is formed a collar 40, Figs. 5 and 6, 10 said collars serving as bearings for coiled springs 41, fitted in recesses 42, which act to normally hold the cutters away from the wire. Levers 43, 44, the latter of which is also shown in Figs 1 and 10, are pivoted at 15 43, to lugs 46, 47, upon opposite sides of the parts 3. Tapped into the end of the short arm of each of said levers, is an adjusting screw 48, which bears against the outer end of the cutter body, and is secured in any desired position by means of lock-nuts 49. The long end of the lever 43, is jointedly connected at 50, Fig. 6, to a horizontal bar 51, while the corresponding arm on the lever 44 is jointedly connected at 52 to a horizontal bar 53, 20 parallel with and corresponding to the bar 51. One end of the bar 51 is jointedly connected at 54, Fig. 7, to a lever 55, which is pivoted at 56 to a lug 57, at one end of the frame of the machine. The corresponding 25 end of the bar 53 is connected in like manner at 58, with a like lever 59 connected with the same lug and arranged parallel to the lever 55. Handles 60, 61, enable said levers to be actuated independently of each other, 30 thereby permitting the bars to be moved longitudinally.

In the operation of my improved machine, it is desirable that its movement should be automatically arrested as soon as the requisite length of wire to properly connect and fasten the staves together is fed into the holes. This result may be accomplished by the following described means: Mounted loosely upon the shaft 18, which is extended 35 beyond its fellow, is a driving pulley 62, Figs. 2 and 3, having a clutch member 63 adapted to be engaged by a counterpart clutch member 64 splined upon said shaft and adapted to slide longitudinally thereon. 40 A collar 65, is rigidly secured to the shaft and serves as an abutment for a coiled spring 66, which is interposed between said collar and the sliding clutch member 64, and tends to cause the engagement of said members 45 when they are not otherwise held out of con-

tact. A bar 67 is arranged parallel to the shaft 18, being rigidly supported upon arms 68, Figs. 1, 2 and 3, which are bolted to the base-plate. Loosely mounted upon the bar 67 is a slide, generally designated by 69, the 50 body 70 of which is bored to receive said bar. Integral with said slide portion is a collar 71, which is loosely fitted in a groove 72, formed in the periphery of the clutch member 64. A split-nut consisting of jaws 73, 75 74, is pivotally and slidably mounted upon the bar 67, each of said jaws being provided with internal screw-threads adapted to engage a screw-threaded portion 75, upon the shaft 18. Arms 76, Figs. 1 to 3 inclusive, 80 are formed upon said jaws and are normally held apart by means of an interposed coiled spring 77, thereby causing the threaded jaws to engage said screw. Said device is adapted to slide upon the part 70. Adjustably attached to the part 70, by means of a set-screw 78, is a collar 79, Fig. 2, between which and a washer 80, abutting against the split-nut, is a coiled spring 81, which exceeds in power the spring 66, for the purpose 90 hereinafter stated. Formed upon the collar 71 is an arm 82, Fig. 4, which is bored to receive a pin 83, having an enlarged head 84. A diminished portion 85 is formed upon said pin, which is adapted to enter a bore 95 86, also shown in Fig. 2, in the bar 67. A collar 87 is attached to the body portion, between which and the arm 82, is interposed a coiled spring 88, which tends to press the pin downwardly into the bore 86, when in 100 registration therewith, to hold the clutch member 64 out of engagement as hereinafter stated.

The operation of my improved machine is as follows: The staves having been placed 105 in the forms and locked in place as hereinbefore described, and the wires 28, for the several forms having been placed between the feeding rolls 25, 26, the operator then grasps the arms 76, Figs. 2 and 3, of the 110 split-nut and presses them together when said nut is moved toward the left to its required position for engagement. The arms are then released when the threads of the nut engage those of the screw portion of the 115 shaft. At this time the spring 81 being expanded, its influence upon the slide 69, is practically nil, while the spring 66 is under compression. The driving pulley 62 is assumed to be continuously rotated. The operator then grasps the head 84 of the locking pin and withdraws the latter from the bore 86. The spring 66, being then free to act, forces the clutch-member 64 into engagement with its fellow, thereby actuating 120 the driving shaft 18, and with it, the feed-rolls, which causes the several wires 28 to be unwound from their respective reels, not shown, and to be simultaneously fed through the guides and bending rolls and thence into 125 130

and through the respective stave holes until the ends project from the holes in the last stave of the series, when the motion of the driving mechanism is arrested through the following described action of the automatic stop mechanism. The rotation of the driving shaft serves, through the action of the screw 75, to move the split-nut to the right into the position shown in Fig. 2. This action results in the compression of the spring 81 and the consequent movement of the slide 69 and collar 71, thereby disengaging the clutch members and moving the slide until the reduced portion 85 of the locking pin is caused to enter the bore 86, thereby holding the clutch out of engagement, with the spring 66 compressed ready to throw the clutch member 64 into engagement when the slide is again unlocked. The spring 81, being more powerful than the spring 66, overcomes the resistance of the latter when sufficiently compressed by the action of the split-nut, resulting in a sudden disengagement of the clutch and a consequent stoppage of the feeding mechanism. As soon as this occurs, the operator grasps the handles of the cutting device, 60, 61, and simultaneously moves them in opposite directions. This action causes the bars 51, 53, to be correspondingly actuated, as indicated by the arrows in Fig. 6, which, in turn, serves to move the levers 43, 44, thereby forcing the cutters upon the cutter-bars 36, 37, which are normally held apart by the springs 41, 45 against the wires 28. Assuming the adjusting screws 48, to be properly adjusted, the action will be uniform with all the cutters of the series and all the wires will be simultaneously severed and the points swaged into the tapered form as described. The staves are then removed, the forms refilled and the operation repeated.

While I prefer to use the automatic stopping mechanism described, I do not limit myself thereto inasmuch as the machine may be operated without it, but in a less satisfactory way. In Fig. 11 I have shown a modification in which a driving pulley 89 is attached directly to the shaft 18. By employing the usual belt shifting mechanism the machine may be controlled by the operator, provided that care be taken to watch the feeding of the wires.

While I have shown a stave-holder of convolute form in cross section, I do not wish to be confined thereto, as it is obvious that any construction whereby the meeting faces of the first and last staves may be separated to permit the bands to enter one and protrude from the other, may be employed without departing from the principle of my invention. Moreover, it is only necessary to arrange the staves in a curved form when the holes therein are curved instead of straight, but inasmuch as I prefer the curved

holes as offering superior advantages in the finished structure, I have indicated a form adapted to meet that condition. In the event that the holes were made straight from edge to edge of the stave, it is manifest that the form itself may be made straight in cross section in which case the wire bending mechanism would, of course, be dispensed with.

Having thus described my invention, I claim:

1. A machine for threading bands in staves which are formed with band holes therein extending through said staves from edge to edge, said machine comprising in combination a stave holding element for holding the staves with their edges juxtaposed to permit the holes therein to register with each other, band feeding devices adjusted to guide and feed the bands into and through said holes, and means for actuating said feeding devices.

2. A machine of the class described, in which is combined a stave holding form for holding staves with their edges adjacent to each other without bending the bodies of the staves, said staves having band receiving holes therein extending from edge to edge, the holes being held in registration by said form, band guides adjacent to one edge of one of said staves, said guides being in registration with the holes therein, and means for feeding bands through said guides into and through the respective registering holes.

3. A machine of the class described, in which is combined a stave-holding form, band guides arranged to register with curved holes previously formed through the staves from edge to edge thereof, means for feeding bands therein through said guides, and means for imparting a curve to said bands to conform substantially to the curve of said holes.

4. A machine of the class described, in which is combined a clamping element for rigidly securing a number of staves having beveled edges with said edges in such relation to each other as to cause the body of each stave to lie in a plane at an angle to that of the one adjacent thereto, each of said staves having a plurality of holes therein extending from edge to edge for the reception of retaining bands, means for adjusting said staves to cause registration of the holes, and means for simultaneously guiding and projecting bands into and through said holes.

5. A machine of the class described, in which is combined a stave-holding form, band guides arranged to register with holes previously formed in the staves, means for feeding bands therein, and means for severing said bands to permit the removal of the assembled staves with the bands therein.

6. A machine of the class described in

which is combined a stave holding form arranged to hold the meeting edges of the first and last staves apart from each other to permit the entry and exit of bands into and 5 from holes previously formed from edge to edge of the several staves and means for threading bands into said holes.

7. A machine of the class described, in which is combined a stave-holding form arranged to hold the meeting edges of the first and last staves away from each other, to permit the bands to enter the holes in the first and to protrude from those in the last stave, means for adjusting said staves to 10 cause registration of the respective series of 15 holes, and means for simultaneously threading bands into the holes.

8. In a machine of the class described, the combination of a stave-holding form arranged to hold the meeting edges of the first and last staves away from each other, to permit the bands to enter the holes in the first and pass out from those in the last stave, means for causing end registration of 20 25 the staves, feed rolls for simultaneously actuating all of the bands, guides for said bands, in registration with the stave holes and means for simultaneously severing all of said bands.

30 9. In a machine of the class described, the combination of a stave-holding element, means for threading a plurality of bands from separate sources of supply of indefinite length into holes formed in said staves, means for severing said threaded bands from the respective sources of supply and means for taperingly forming the ends of 35 said bands when severed.

10. In a machine of the class described, the combination of a stave-holding form, means for threading a plurality of bands from a continuous source of supply into 40 holes formed in the staves, feeding mechanism, means for arresting said feeding mechanism when the bands are inserted and means for severing said bands.

11. In a machine of the class described, the combination of a stave-holding form, means for threading a plurality of bands from a continuous source of supply, into 45 holes formed in the staves, feeding mechanism, means for arresting the same when the bands are inserted, and means for simultaneously severing the bands.

12. In a machine of the class described, 55 the combination with a stave-holding form, means for threading a plurality of bands, from a continuous source of supply into holes formed in the staves, feeding mechanism, means for arresting the same when 60 the bands are inserted, means for severing the bands and means for tapering the entering ends of the bands for the next succeeding set of staves.

13. A machine of the class described in 65 which is combined means for holding a plurality of staves having band-receiving holes therein with the edges of said staves in juxtaposition and the holes in registration, band-feeding devices adjusted to guide and 70 feed bands into said holes, means for actuating said feeding devices and means for automatically arresting the same when the bands are inserted.

14. A machine of the class described, in 75 which is combined convolute stave-holding forms and means for clamping the staves therein, with the meeting faces of the first and last staves at different distances from the axis of the form.

15. In a machine of the class described, the combination of a form for holding bored staves with their meeting edges in juxtaposition, means for clamping said staves in place, and yielding means arranged to press 80 85 against one face of the several staves to hold the opposite face against the form.

16. A machine of the class described in which is combined a convolute stave-holding form, for gaging staves with respect to band receiving holes therein, a counterpart yielding core and means for clamping staves in 90 said form against said yielding core whereby the outer faces of the staves are caused to contact uniformly with the inner faces of 95 the form.

17. A machine of the class described in which is combined a convolute stave-holding form, a yielding counterpart core, and means for compressing the staves against said core. 100

In testimony whereof, I have signed this specification in the presence of two subscribing witnesses, this 16th day of July 1908.

DAVID E. VANVACTOR.
